United States Patent Office

Des. 185,074
Patented May 5, 1959

185,074

RUBBER SHEET FABRIC

Ruth F. Emmet, Dover, Del., assignor to International Latex Corporation, Dover, Del., a corporation of Delaware

Application February 6, 1959, Serial No. 54,495

Term of patent 14 years

(Cl. D87—3)

The figure is a plan view of a rubber sheet fabric showing my new design.

I claim:

The ornamental design for a rubber sheet fabric, as shown.
